UNITED STATES PATENT OFFICE

WESLEY J. SHAW, OF HAVERHILL, MASSACHUSETTS, ASSIGNOR TO NEW ENGLAND WOOD HEEL CO., OF HAVERHILL, MASSACHUSETTS, A CORPORATION OF MASSACHUSETTS

REPAIRED LAST

Application filed September 6, 1927. Serial No. 217,615.

The present invention, though having also other fields of usefulness, is more particularly related to shoe lasts and their manufacture.

5 In the manufacture of shoes, it is customary to secure an insole temporarily to the sole of a wooden last by tacking. The sole of the last is frequently covered with a sheet-metal plate, and the latter is provided with 10 several perforations through which the tacks are driven into the wood. Repeated tack driving wears away the wood near the perforations, and the last becomes useless. The tack-pierced wood may, of course, be replaced 15 by a wood plug, but the driving of tacks into such plug causes the plug to split, and for other reasons also the life of the repair is very short. Other types of plugs have also 20 been proposed, but without marked improvements.

It is therefore an object of the present invention to improve upon last manufacture, to the end that the life of the last may be lengthened and its efficiency increased, 25 though at comparatively slight cost. Other and further objects will be explained herein-after and will be particularly pointed out in the appended claim.

With the above ends in view, a feature of 30 the invention consists in replacing the tack-driven wood by a plug of suitable material, such as rubber, compressed very solidly. The tacks are very easily driven into this plug, but without wearing the compressed rubber 35 to any material degree. Preferably, the sole of the last is first drilled to provide a suitable recess, the plug is provided in the form of a frustum of a cone, the larger end of which is wider than the diameter of the recess, and 40 the plug is then driven into the recess, causing the said larger end to become compressed therein.

The invention will now be explained more 45 at length in connection with the accompanying drawings, in which Fig. 1 is an elevation of a last, partly in section, after it has been drilled, in readiness to receive the rubber plugs; Figs. 2 and 3 are views illustrating the 50 method of the present invention; and Fig. 4

is a similar view showing the completed article.

Recesses 2 are drilled in a last at the places where the wood has been worn away by the tacks. These recesses are aligned with the perforations provided in the metal plate 6 if such a plate is secured to the sole of the last. A conical rubber plug 8 is then driven into each recess, with the smaller end foremost. The rubber or other material of the plug should be of such consistency that it is soft enough to permit the tacks to be driven thereto and yet sufficiently dense so that the tacks driven thereto form holes of very small dimension when the tacks are withdrawn, the rubber closing up again over the hole formed by the removed tacks so as practically to destroy all trace of the hole. Rubber such as is used in the making of rubber heels has been found to answer the purpose very well. All 60 such materials are herein referred to under the generic term "rubber." The rubber plug is finally cut flush with the sole of the last or with the plate 6.

Modifications will readily occur to persons skilled in the art and are considered to fall within the spirit and scope of the invention as defined in the appended claim.

What is claimed is:

A last having a recess and an elastic plug in the recess to provide a surface through which nails may be driven, the rubber being soft enough to permit nails to be driven thereto, but sufficiently dense so that nails driven thereto form holes of relatively small dimensions when withdrawn from the plug, and the elasticity of the rubber being such that when a nail is removed therefrom the rubber of the plug closes up over the hole formed by the removal nail so as practically to destroy 90 all traces of the hole.

In testimony whereof, I have hereunto subscribed my name.

WESLEY J. SHAW.
